(57) CLAIM

We claim the ornamental design for a bag, as shown and described.

DESCRIPTION

FIG. 1 is a perspective view showing our design for a bag; FIG. 2 is another perspective view thereof; FIG. 3 is another perspective view thereof; FIG. 4 is a front elevation view thereof; FIG. 5 is a back elevation view thereof; FIG. 6 is a left side elevation view thereof; FIG. 7 is a right side elevation view thereof; FIG. 8 is a top plan view thereof; and, FIG. 9 is a bottom plan view thereof.

In the drawings, the long dashed broken lines showing a handbag depict environment and form no part of the claim. The short evenly dashed broken lines in the figures depict stitching and form no part of the claim.
